UNITED STATES PATENT OFFICE.

LEO JNO. BAYER, OF ST. LOUIS, MISSOURI.

SOOT BOILER-CLEANER.

1,115,486.

Specification of Letters Patent.

Patented Nov. 3, 1914.

Application filed March 12, 1914. Serial No. 824,279.

To all whom it may concern:

Be it known that I, LEO JOHN BAYER, citizen of the United States, residing at St. Louis, State of Missouri, have invented 5 certain new and useful Improvements in Soot Boiler-Cleaners, of which the following is a full, clear, and exact description, reference being had to the accompanying drawings, forming a part hereof.

10 My invention has relation to improvements in soot boiler-cleaners; and it consists in the novel details of construction more fully set forth in the specification and pointed out in the claims.

15 In the drawings, Figure 1 is a combined section and side elevation of a conventional water-tube boiler of the Heine type, showing my invention applied thereto, the parts in section being in the plane of the section 20 line 1—1 of Fig. 3; Fig. 2 is a horizontal section on the line 2—2 of Fig. 1 of one-half of the boiler immediately above the upper deflecting wall or baffle, the other half being removed to expose beneath it the 25 half of the lower portion of the boiler immediately above the lower deflecting wall or baffle; Fig. 3 is a front elevation of the boiler with my invention applied thereto; and Fig. 4 is a perspective (broken away) 30 of the nozzle installation leading from the headers detached.

The present invention is an extension of the construction forming the subject-matter of U. S. Letters Patent Number 1,032,583, 35 dated July 16, 1912, issued to me for soot boiler-cleaners, and has for its object the elimination of the blower installation on the rear of the boiler, whereby a single blower, and that confined to the front of 40 the boiler, will serve the purpose of cleaning the boiler and removing the objectionable soot and other accumulations which deposit over the heating surfaces exposed to the products of combustion. By dispensing 45 with the rear blower, the cost of installation and operation is materially reduced, the single front blower (or cleaner) according to my present invention, performing in boilers which are not too long, the 50 functions of the front and rear blowers now so generally installed on boilers of the Heine and kindred water-tube types.

The advantages of the present invention will be fully apparent from a detailed description thereof which is as follows:

Referring to the drawings, S, represents

a boiler shell having terminal water-legs L, L, connected by circulating water-tubes T. Extending over the fire-box B, and above the bridge-wall W, and a suitable distance 60 over the rear combustion chamber C, and disposed at the bottom of the water-tubes T, is a deflecting wall or horizontal baffle a, said baffle terminating so as to leave an opening or pass o, between it and the rear 65 water-leg as well understood in the art. Disposed at the top of the water-tube section of the boiler and extending from the rear water-leg forward a suitable distance so as to leave a pass o', between it and the 70 front water-leg, is a second baffle or deflecting wall b. Leading from a steam supply pipe 1, at the front end of the boiler, and disposed across substantially the center of the front water-leg is a branch or header 2 75 provided with a conventional control valve V at its juncture with the pipe 1, said header being provided on opposite sides with a series of branches or distributing pipes 3, 3, the alternate members of the series terminating 80 at the top in long blowing tubes t, and at the bottom in long blowing tubes t', and at intermediate points in nozzles n, the several tubes and nozzles being inserted through the hollow stay-bolts 4 of the water-leg as 85 well understood in the art. Leading likewise from the steam supply-pipe 1 is a bent pipe P which terminates in a header 2' in substantial alinement with the header 2, said header 2' being likewise provided with distributing pipes 3', 3', which terminate alternately in top and bottom long blowing 90 pipes t t', and with intermediate nozzles n. The branches 3 which alternate with corresponding branches carrying the long terminal tubes t t', are provided with terminal nozzles n', the header 2 carrying intermediate nozzles n'. The branches 3' alternating with corresponding branches carrying the long terminal tubes t t', are provided 95 with terminal and intermediate nozzles n', the nozzles n n' of the several branches being of a length to just pass through the stay-bolts 4, and terminating substantially flush with the inner wall of the water leg. 100

As best seen in Fig. 4, a portion of the branches 3, carry four blowing members t, n, n, t'; a portion of the branches 3', carry four blowing members n', n', n', n'; another portion of the branches 3 together with the header 2 carry three blowing members n', n', n', and another portion of

the branches 3' together with the header 2' carry three blowing members t n t' . With this method of distribution the nozzles n n' of each header 2, 2' are disposed in 5 distinct horizontal planes, the distribution of the nozzles when viewed from the front of the boiler (Fig. 3) being "diamond" shaped as indicated by the dotted diamond figures d in said Fig. 3. At its juncture 10 with the pipe 1, the pipe P is provided with a conventional control valve V'. The stack is indicated by the dotted showing D.

In a boiler baffled horizontally as here indicated, there are, as well understood in the 15 art, three main and distinct zones of precipitation of soot and other material (carried by the gases discharged from the combustion-chamber) apart from what is deposited directly on the tubes T. These zones are indicated by r , r' and r'' , being located substantially and respectively at the rear end 20 of the bottom baffle, at the front end of said baffle against the front water-leg, and at the rear end of the upper baffle against the rear 25 water-leg. As shown by the arrows in Fig. 1, the line of draft is from the fire-box B rearward over the combustion chamber C, through the passage o, thence forward between the tubes T toward the passage o', 30 thence rearward between the shell S and upper baffle b toward the stack D. In the operation of my blower this draft line is not materially disturbed so that whatever soot and fly ash accumulating on the heating 35 surfaces and baffles, is dislodged by the steam jets issuing from the tubes t , t' , and nozzles n n' , will be carried by the draft to the stack D, and through the latter into the atmosphere.

40 As clearly obvious from the drawings, the upper row of tubes t and nozzles n' discharge their jets in the general direction of the draft (rearwardly above the top baffle b), the bottom tubes t' and nozzles n' , and 45 the intermediate nozzles n n' discharging between the baffles (a b) rearwardly but against or in opposition to the general line or direction of draft. The jets which thus 50 oppose the draft being in the majority, it becomes necessary in the operation of the cleaner, to first blow one side and then the other, in order that one-half of the space between the baffles may serve as a conduit through which the draft may freely operate 55 in proper direction (toward the opening o') to carry the soot and ash dislodged by the jets operating in the adjacent half of said space, toward the opening or pass o', after which the natural draft will carry the products 60 through the space between the shell S and upper baffle b to the stack D.

From the foregoing, the operation of the blower will be readily understood and is substantially as follows: It will be seen that the 65 headers 2, 2', are controlled by separate

valves V, V', to permit the headers to be operated independently. To "blow" or clean the boiler we can assume that the valve V' is closed and the valve V open. Under these circumstances, the upper row of tubes 70 t and nozzles n' leading from the branches or distributors 3 attached to the header 2 will discharge over the top baffle b in the general direction of the line of draft, the intermediate nozzles n n' and bottom tubes t' 75 discharging substantially against the draft, the operations of the several tubes and nozzles specified, being confined substantially to one-half of the boiler, the blower devices controlled from the valve V' being shut off. 80 This permits the draft to operate without interruption through the half of the boiler not being blown (as quite obvious from an inspection of Figs. 3 and 4). The tubes t , t' , 85 may be considered as nozzle-extensions or extension nozzles (the conventional nozzle n , n' , terminating at the inner wall of the water-leg L), the extensions t discharging at points in proximity to the precipitation zone r'' , and the extensions t' discharging in the 90 region of the zone r , the zone r' being taken care of by the nozzles n , n' at the bottoms of the branches 3 3'. The jets issuing from the extensions t' expanding as they do more or less after leaving the discharge ends of 95 the extensions, will discharge in a measure toward the half or side of the boiler not being blown, and thus induce a more rapid flow of the combustion products through said half toward the pass o'. At the same time, 100 the discharges from the tubes or extensions t will induce an energetic flow of the products toward and into the stack D; and the soot and fly-ash dislodged by the impact of the jets against the water tubes and bottom 105 baffle on the side being blown will be taken up by the increased draft traversing the half of the boiler not being blown, and carried out of the stack. When one-half of the boiler is blown, the valve V is closed, and 110 valve V' is opened, the blowing of the opposite half then taking place in precisely the same manner, the material dislodged by the jets being carried off to the stack through the half of the boiler not being blown. The 115 installation here shown, and confined to one end of the boiler (there being no blower at the rear), must necessarily be made of at least two independently operable sections, one section, composed of the header 2 with 120 its nozzles, being blown to operate upon one half of the boiler, and the other section, composed of the header 2' with its nozzles, being blown to operate on the adjacent half of the boiler, it being of course immaterial 125 which half is blown first. To operate both sections at one time would not be permissible as in that event the draft would be choked off, and the backing and banking of the fire 130 would result.

The function served by the tubes t' is to dislodge the accumulations in the region of the zone r' and cause them to mingle with the draft traversing the side of the boiler not being blown; the function of the tubes t is to agitate the accumulations in the zone r'' , and bring them into the current of the boiler section not being blown, so as to be ejected through the stack D. The soot dislodged from the tubes and baffles by the nozzles n, n' , is naturally scattered and forced into the current on its way to the stack, so that by first blowing one half or section of the boiler and then the other with the single front installation as here shown, eminently good results may be obtained. Besides, by confining the installation to one end (the front) the cost of the blower, and operating expenses are materially reduced. The nozzles (t, n, n', t') in the present form of blower are distributed over substantially the entire, or at least the major portion of the tube area of the water-leg, that is to say, the area defined or covered by, the ends of the water tubes; and while not every hollow stay-bolt is fitted or provided with a blower nozzle, the number so provided is sufficient for the purpose in view. As well understood in the art, stay-bolts not equipped with nozzles are plugged up to prevent air being drawn into the spaces between the tubes T. Features shown but not alluded to are well known in the art and description thereof is here unnecessary.

Having described my invention, what I claim is:

1. In combination with a boiler having a water-tube section comprising circulating water-tubes communicating with the boiler, said tubes being provided with a bottom horizontal baffle terminating at the rear a suitable distance from the adjacent ends of the tubes, and with an upper baffle terminating in the front a suitable distance from the adjacent ends of the tubes, a furnace provided with a fire-box and a combustion chamber beneath the bottom baffle, a front blower provided with a series of nozzles disposed over the major portion of the area defined by the tube terminals and discharging rearwardly between the baffles, and suitable extension nozzles discharging rearwardly above the bottom baffle in the region of initial precipitation of suspended impurities carried by the gases discharged from the combustion chamber.

2. In combination with a boiler having a water-tube section comprising circulating water-tubes communicating with the boiler, said tubes being provided with a lower horizontal baffle terminating at the rear a suitable distance from the adjacent ends of the tubes, and with a second baffle superposed over the first baffle and terminating in the front a suitable distance from the adjacent ends of the tubes, a furnace provided with a

fire-box and combustion chamber beneath the lower baffle, a front blower comprising two independently operable sections and provided with a series of nozzles disposed over the major portion of the area defined by the tube terminals and discharging rearwardly between the baffles, and suitable extension nozzles discharging rearwardly above the lower baffle, in the region of the zone of initial precipitation of suspended impurities carried by the gases discharged from the combustion chamber.

3. In combination with a boiler having a water-tube section comprising circulating water-tubes communicating with the boiler, said tubes being provided with a lower horizontal baffle terminating at the rear a suitable distance from the adjacent ends of the tubes, and with a second baffle superposed over the first baffle and terminating in the front a suitable distance from the adjacent ends of the tubes, a furnace provided with a fire-box and combustion chamber beneath the lower baffle, a front blower comprising two independently operable sections and provided with a series of nozzles disposed over the major portion of the area defined by the tube terminals, and discharging rearwardly between the baffles and above the upper baffle, and suitable extension nozzles discharging rearwardly above the lower baffle, in the region of the zone of initial precipitation of suspended impurities carried by the gases discharged from the combustion chamber.

4. In combination with a boiler having a water-tube section comprising circulating water-tubes communicating with the boiler, said tubes being provided with a lower horizontal baffle terminating at the rear a suitable distance from the adjacent ends of the tubes, and with a second baffle superposed over the first baffle and terminating in the front a suitable distance from the adjacent ends of the tubes, a furnace provided with a fire-box and combustion chamber beneath the lower baffle, a front blower comprising two independently operable sections and provided with a series of nozzles disposed over the major portion of the area defined by the tube terminals, and discharging rearwardly between the baffles and above the upper baffle, and suitable extension nozzles discharging rearwardly above the lower and upper baffles respectively, in the regions of the zones of precipitation of suspended impurities on said baffles.

5. In combination with a boiler having a shell, and a water-tube section comprising a front and rear water-leg and connecting circulating tubes, a lower horizontal baffle extending from the front water-leg to a point removed a suitable distance from the rear water-leg, a combustion chamber below the lower baffle, a second baffle above the first

100

baffle extending from the rear water leg to a point removed a suitable distance from the front water-leg, a front blower comprising independently operable sections provided with nozzles passing through the front water-leg and distributed over the major portion of the tube area of said leg, said nozzles discharging rearwardly, a portion of the nozzles being extended above the lower baffle and discharging in the region of the zone of initial precipitation of suspended impurities on said baffle, another portion of the nozzles being extended across the space between the front water-leg and adja-

cent end of the upper baffle and over the upper baffle and terminating to discharge in the region of the zone of precipitation of suspended impurities on said upper baffle, and means for conducting the dislodged soot and other material to a point outside the boiler-furnace. 15 20

In testimony whereof I affix my signature, in presence of two witnesses.
